UNITED STATES PATENT OFFICE.

JOHN BEAVOR-WEBB, OF NEW YORK, N. Y., ASSIGNOR TO ALEXANDER J. LEITH, OF SAME PLACE.

YOKE-FRAME FOR CABLE ROADS.

SPECIFICATION forming part of Letters Patent No. 394,801, dated December 18, 1888.

Application filed July 10, 1888. Serial No. 279,529. (No model.)

To all whom it may concern:

Be it known that I, JOHN BEAVOR-WEBB, a citizen of Great Britain, and a resident of New York city, county, and State, have invented 5 a new and useful Improvement in Yoke-Frames for Cable Roads, of which the following is a full, true, and exact description, reference being had to the accompanying drawings.

10 My invention relates to a pressed-steel flange yoke-frame made in one piece and arranged to support the rails and to carry the cable and cable mechanism in a chamber provided therefor, and which may likewise be 15 provided with an opening or openings, through which electric conductors or other bodies may extend.

The present yoke-frames generally employed are made of a number of pieces bolted 20 together, which are liable to become loosened or detached, and which are, at the best, expensive and insecure. In some cases cast-iron yoke-frames have been made, which, however, are liable to break under the jar of 25 travel, and consequently have to be supported by various devices.

By my invention the cast-iron sometimes employed is dispensed with and the yoke-frame itself is stamped from a single piece of 30 wrought-steel. The flanges project upon one side, and when the yoke-frame is set in the ground they form an important function in holding the yoke-frame in the ground, the earth or other filling surrounding and pressing 35 into the spaces between the flanges.

My invention will be readily understood from the accompanying drawings, in which—

Figure 1 represents a vertical elevation partly in section; and Fig. 2, a central vertical section through Fig. 1, partly in perspective.

The yoke-frame itself is preferably of approximately the shape shown; and consists, generally, of the two arms H H, extending 45 laterally and supporting the rails R R, and two central supporting parts, K K, upon which the slot-irons E E are supported, and of a central opening, G, through which the cable channel or tube passes.

50 The yoke-frame is arranged with an upper flange, B, and a lower flange, C, and also with internal flanges, D, surrounding the openings

F, arranged for the reception of electric wires or other bodies. These internal flanges, D, both assist in strengthening that part of the 55 yoke-frame and also co-operate in holding the yoke-frame firmly in the ground when packed in position. The rails R and slot-irons E may be bolted to the yoke-frame or secured in any other suitable manner, the 60 flange B serving as a support and rest, upon which they may be securely fastened. It is obvious that I may add one or more additional openings to this, as shown—as, for instance, an opening in the bottom of the yoke-frame, 65 if desired. It is obvious, likewise, that, though the flange is shown as continuous around the external edge of the yoke-frame, and though that is the best construction, a part of it may be omitted without losing altogether the benefits of my invention. 70

What I claim as my invention, and desire to secure by Letters Patent, is—

1. A pressed-steel flanged yoke-frame for cable roads, having a continuous flange integral therewith and surrounding its exterior edge and likewise the cable-opening, substantially as described. 75

2. A pressed-steel flanged yoke-frame for cable roads, made in one piece and having the flanges C B integral therewith, substantially as described. 80

3. The pressed-steel flanged yoke-frame for cable roads, made of one piece, having the flange B C, the arms H H, and intermediate supports, K K, substantially as described. 85

4. The pressed-steel flanged yoke-frame for cable roads, consisting of a flanged steel plate having the arms H H, the supports K K, and the openings F F, substantially as described. 90

5. The pressed-steel flanged yoke-frame for cable roads, made of one piece, having the flange B C, the arms H H, the rails R R, supported thereon, the intermediate supports, K K, and the slot-irons E E, supported thereon, substantially as described. 95

In testimony whereof I have signed my name to this specification in the presence of two subscribing witnesses.

J. BEAVOR-WEBB.
